PROCESS OF PRODUCING SHEET GLASS

Luke C. Mambourg, Lancaster, Ohio, assignor to
 Libbey-Owens-Ford Glass Company, Toledo,
 Ohio, a corporation of Ohio

Application July 15, 1932, Serial No. 622,709

3 Claims. (Cl. 49—87)

The present invention relates to an improved process of forming sheet glass.

This invention is of particular utility when incorporated in a rolling machine for producing continuous sheet glass wherein a pair of horizontally arranged forming rolls are positioned above a working receptacle containing a mass of molten glass, said rolls being arranged relative to one another to create a vertical sheet forming pass therebetween and being positively driven in a manner to draw a relatively heavy body of glass upwardly from the molten mass and reduce it to a sheet of substantially predetermined and uniform thickness. The sheet, after being formed, is preferably drawn upwardly for a relatively short distance and then deflected into the horizontal plane about a rotatable bending roll. With the above type of rolling machine, one of the forming rolls is ordinarily mounted in a fixed position while the other roll is movable toward and away from the fixed roll.

Heretofore, it has been customary to urge the movable forming roll toward the fixed forming roll by means of a counterweight, and to provide an adjustable stop member for limiting the movement of said rolls toward one another. Furthermore, it has also been the usual practice to provide sufficient weight to maintain the movable roll at all times against the stop member except upon the passage of foreign matter or clay stones between the rolls, at which time the movable roll would be permitted to temporarily move away from the fixed roll. In other words, the pressure exerted by the counterweight to hold the movable roll against the stop member was such that during the normal rolling operation, the movable roll would be held in a fixed position and only under unusual circumstances, such as to permit the passage of clay stones or the like therebetween, would this roll be moved away from the fixed roll. Thus, the distance between the fixed and movable rolls determined the thickness of sheet produced. That is to say, the thickness of sheet produced was equal to the width of the pass between the forming rolls which was controlled by adjustment of the stop member. I have found, however, that when sufficient weight is provided to maintain the movable roll always against the stop member as explained above, a rolling pressure greater than that required to roll the glass to sheet form is had, and that this excessive rolling pressure tends to cause a stagnation and devitrification of the glass below the forming rolls resulting in the formation of so-called darts or streaks in the sheet. These darts are nothing more or less than devitrified glass which is drawn upwardly into the sheet.

The principal aim and object of this invention is to obviate the tendency of the glass to become stagnant beneath the forming rolls and thereby

do away with the formation of darts or streaks in the sheet resulting in the production of glass of an improved quality.

Briefly stated, according to the present invention, the stop member referred to hereinabove for limiting the movement of the movable forming roll toward the fixed forming roll is eliminated and the said movable roll permitted to fluctuate toward and away from the said fixed roll so that the thickness of sheet produced will be governed by the weight of the counterweight and the viscosity of the glass being rolled. In other words, only sufficient pressure is exerted upon the glass being rolled to produce a sheet of the desired thickness so that no excessive rolling pressure is had. Consequently, the thickness of sheet produced is controlled by varying the pressure of the movable roll upon the glass being rolled.

Other objects and advantages of the invention will become more apparent during the course of the following description when taken in connection with the accompanying drawing.

In the drawing forming a part of this application and wherein like numerals are employed to designate like parts throughout the same,

Fig. 1 is a vertical longitudinal section through one type of sheet glass rolling apparatus with which the present invention may be incorporated,

Fig. 2 is a side elevation, partially in section, of the supporting means provided for each end of the forming and bending rolls, and

Fig. 3 is a plan view of the counterweight.

Referring now to the drawing, and particularly to Fig. 1, the numeral 5 designates a relatively shallow working receptacle or pot containing a mass of molten glass 6 supplied thereto from any suitable type of glass melting furnace 7. The working receptacle 5 is ordinarily supported upon stools 8 arranged within a heating chamber 9.

Positioned above the working receptacle and extending transversely thereof is a pair of horizontal sheet forming rolls 10 and 11 arranged relative to one another to create a vertical sheet forming pass therebetween. The forming rolls are adapted to be positively driven in any desired manner so that upon rotation thereof, the said rolls will function to draw a relatively heavy body of glass 12 upwardly from the molten mass 6 and reduce the same to a sheet 13 of substantially predetermined and uniform thickness. As herein shown, the glass sheet 13 is continued upwardly for a relatively short distance beyond the forming rolls 10 and 11 and is then deflected about a rotatable member or roll 14 into a substantially horizontal plane wherein it is supported and carried along upon a 60

series of horizontally arranged conveyor rolls 15 into an annealing leir (not shown).

The means herein provided for adjustably supporting the forming rolls 10 and 11 and bending roll 14 is illustrated in Fig. 2, and to this end there is mounted longitudinally above the working receptacle 5, adjacent each side thereof, a pair of spaced horizontal supporting beams 16, one only being shown. Arranged inwardly of adjacent beams 16 are slides 17 on which is adapted to slide a casting 18. Each casting is provided with transverse openings 19 and through each of these openings passes a bolt 20, said bolts connecting the adjacent beams 16 together and preventing separation thereof. The openings 19 are elongated so that the casting 18 can be moved longitudinally of the machine within certain limits depending upon the length of said openings.

Each casting 18 carries a vertical sleeve member 21 through which extends a bolt 22, said bolt having a threaded upper end 23 working through a worm wheel 24 with which meshes a worm 25 carried upon a shaft 26. Upon rotation of shaft 26, rotation will be imparted to the worm 25 and worm wheel 24, thereby raising or lowering the bolt 22 depending upon the direction of rotation of the said shaft.

Each supporting bolt 22 carries a depending casting 27 by means of a cross pin 28 extending through the bolt and also through apertured ears on said casting. Two additional members 29 and 30 are also carried by the bolt 22, the casting 27 and members 29 and 30 being tied together by means of bolts 31. These three parts 27, 29 and 30 constitute supports for the forming roll 10 and bending roll 14.

The forming roll 10 is preferably maintained stationary during the rolling operation although it is of course rotatable about its axis and may be adjusted vertically with respect to the mass of molten glass from which the sheet is produced. The forming roll 11, however, is mounted in such a manner that it is freely movable toward and away from roll 10. The mounting for the roll 11 includes a link 32 pivotally connected by a pin 33 between the ends 34 of the bracket or part 30. The link 32 is likewise pivoted as at 36 to a support 35 for the roll 11. A second link 37 is pivotally connected at 38 to the ends 34 of bracket 30 and is also pivoted intermediate its ends to the roll support 35 by a pin 39.

A bell crank lever 40 pivoted intermediate its ends as at 41 to the casting 18 is connected to the upper end of link 37 by a connecting link 42 pivoted at one end to the bell crank as at 43 and at its opposite end to said link 37 as at 44. A connector arm 45 is pivotally associated with the bell crank as at 46 and is also pivotally connected to a beam 47 at 48. The beam 47 is pivotally supported as at 49 on the cross beam 50, while the opposite end of the beam carries a plurality of weights 51. These weights are preferably in the form of metal discs removably mounted upon a cross pin 52 and held in place by nuts 53.

With the type of linkage above described and when the various parts are arranged in the position illustrated in Fig. 2, it will be seen that the discs 51 constitute a counterweight which acts to urge the movable forming roll 11 toward the fixed forming roll 10. As pointed out hereinabove, it

has heretofore been customary to provide an adjustable stop member to limit the inward movement of roll 11 toward roll 10 and thereby control the space between the said rolls and consequently the width of the sheet forming pass. Moreover, the pressure exerted upon the roll 11 was such as to maintain the said roll against the stop member during the normal rolling operation so that the sheet produced was of a thickness equal to the width of the forming pass. The disadvantages incident to the use of such a stop member have also been fully set forth above.

According to the present invention, therefore, this stop member has been eliminated, with the result that the roll 11 is permitted to float toward and away from roll 10. In other words, no means is provided to limit or restrict the movement of roll 11 toward roll 10. With such an arrangement, the thickness of sheet produced will be governed by the weight of the counterweight and the viscosity of the glass being rolled. Thus, only sufficient pressure is exerted upon the glass being rolled to produce a sheet of the desired thickness so that no excessive rolling pressure is had. That is to say, the rolls will not be caused to assume a definite relation to each other, and in this way the rolling pressure will not be sufficient to cause a stagnation of the glass below the rolls and the disadvantages incident thereto. The thickness of sheet produced is controlled by varying the pressure of the movable roll upon the glass being rolled, and this pressure can be varied by increasing or decreasing the number of weights 51.

It is to be understood that the form of the invention herewith shown and described is to be taken as the preferred embodiment of the same, and that various changes in the shape, size and arrangement of parts may be resorted to without departing from the spirit of the invention or the scope of the subjoined claims.

I claim:

1. In the manufacture of sheet glass wherein a relatively heavy body of molten glass is passed between a pair of revolving rolls and reduced thereby to a sheet of substantially predetermined thickness, the step of controlling the thickness of the sheet produced by causing said rolls to exert a pressure upon the glass sufficient only to form a sheet of the desired thickness.

2. The process of producing sheet glass, which consists in passing a relatively heavy body of molten glass upwardly between a pair of revolving rolls which serve to reduce the same to a sheet of substantially predetermined thickness, in arranging one of said rolls so that it is freely movable toward and away from the other roll, and in controlling the thickness of the sheet produced by causing said rolls to exert a pressure upon the glass sufficient only to form a sheet of the desired thickness.

3. The process of producing sheet glass, which consists in passing a relatively heavy body of molten glass between a pair of revolving rolls which serve to reduce the same to a sheet of substantially predetermined thickness, in arranging one of said rolls so that it is freely movable toward and away from the other roll, and in controlling the thickness of the sheet produced by varying the pressure of the movable roll upon the glass being rolled.

LUKE C. MAMBOURG.
